[57] CLAIM

The ornamental design for a tilttable mixing bowl support, as shown and described.

DESCRIPTION

FIG. 1 is a front, top and side perspective view of the tilttable mixing bowl support showing our new design;
FIG. 2 is a front elevational view thereof;
FIG. 3 is a rear elevational view thereof;
FIG. 4 is a side elevational view thereof, the opposite side being unadorned and similar to the side shown with the exception of the lever and slot;
FIG. 5 is a top plan view thereof; and,
FIG. 6 is a bottom plan view thereof.
